United States Patent Office

Des. 218,343
Patented Aug. 11, 1970

218,343

CLOCK HANDS

Herbert E. Spencer, Grandville, Mich., assignor of one-half to Judith Helen Spencer

Filed June 23, 1969, Ser. No. 17,815

Term of patent 14 years

Int. Cl. D10—06

U.S. Cl. D42—1

FIG. 1.

FIG. 2.

FIG. 1 is a front elevation view of clock hands showing my new design; and

FIG. 2 is a right side elevational view thereof.

I claim:

The ornamental design for clock hands, substantially as shown.
